APPARATUS FOR TREATING CONTINUOUS FILAMENTARY BUNDLES

Elvin L. Coe, Nitro, and William P. Dooley, South Charleston, W. Va., assignors to American Viscose Corporation, Philadelphia, Pa., a corporation of Delaware

Application November 3, 1951, Serial No. 254,752

7 Claims. (Cl. 68—181)

The present invention relates to apparatus for treating continuous filamentary bundles. It is concerned particularly with the removal from the bundle of by-product materials loosely carried out of a liquid treating bath by the bundle and the recovery of these materials, especially from freshly coagulated bundles or tows of viscose filaments.

It is an object of the present invention to provide an improved and highly efficient apparatus for washing a continuous filamentary bundle of freshly spun and coagulated and/or regenerated viscose. It is another object to obtain the materials removed by a washing treatment in sufficient concentration to render recovery thereof practical. A more specific object is to provide an apparatus for removing carbon disulfide and spinning bath chemicals from large continuous bundles or tows of viscose rayon filaments. It is still another object to provide apparatus which is easily laced and mechanically simple yet capable of being adapted to a variety of operating conditions to obtain or recover materials in concentrations or quantities which warrant the practice of the invention. Other objects, features and advantages of the invention will be apparent from the following description and the drawing relating thereto in which:

Fig. 1 is a diagrammatic elevation of staple fiber making equipment;

Fig. 2 is a fragmentary section through a modified device for washing a filamentary bundle;

Fig. 3 is a section along line III—III of Fig. 2;

Fig. 4 is a top view of a portion of the apparatus illustrated in Fig. 1;

Fig. 5 is a perspective of the guides;

Fig. 6 is a view illustrating a modified system for raising and lowering the cover for the apparatus;

Fig. 7 is a transverse vertical section in elevation of modified apparatus for treating a plurality of strands;

Fig. 8 is a fragmentary section of the apparatus shown in Fig. 7 taken along line VIII—VIII.

According to this invention, gaseous liquid or particulate materials, and especially carbon disulfide, which are carried by a continuous running bundle of coagulated viscose filamentary material are removed by passing the bundle along a sinuous path extending repeatedly into and out of a heated liquid bath closed off from the atmosphere. Stripping elements for engaging the bundle are positioned along the path immediately after or beyond each submerged portion of the path and serve to direct the bundle out of the bath and to express the bath liquid from the bundle. Guide elements are arranged to guide the tow so that the portions of the bundle supported above the bath are at least as long and preferably substantially longer than the submerged portions.

Fig. 1 shows diagrammatically an apparatus for making staple fiber from viscose spinning solution. A filament-forming viscose solution is extruded from the spinnerets 5 into a liquid coagulant 6 such as an aqueous solution in a tank 7. The small streams discharged from the spin-

2

nerets are immediately coagulated into bundles of filaments which travel a predetermined distance through the bath and pass around guides 9 to godets 10. Comb-like guides 11 are supported adjacent and laterally to each godet to space the laps of the yarn axially on the godet. Preferably two or more laps are provided to establish sufficient frictional contact with the godets to stretch the yarns or the tow constituted of the yarns. Each yarn is wound two or more laps around its respective godet 10 and guide 11 and then passes to a guide 12 to be joined with the yarns discharged from other godets to become a portion of a single tow 14.

The tow 14 carries a substantial amount of the liquid coagulating bath containing sulfuric acid, sodium sulfate, and a polyvalent metal sulfate, such as that of zinc, magnesium or the like besides by-products, including carbon disulfide, hydrogen sulfide, and other sulfur compounds. The tow is supported by means such as one or more guides 15 as it passes toward a container or trough 17 provided with a cover 19. The tow 14 is drawn through the container 17 by driven take-up means such as the pair of rolls 21 and 22 which have axes of rotation canted with respect to each other for advancing a plurality of wraps extending around the rolls in a direction lengthwise of their axes. Rolls 21 and 22 may have a higher linear peripheral speed than godets 10 so that stretching of the filaments occurs along the path of the tow extending between the godets and the take-up rolls. Thus, by such a system, the stretching of the filaments constituting the strand or tow 14 and the stripping thereof may be conducted simultaneously. Moreover, the tension required for stretching effectively promotes stripping action as the tow compacts tightly in passing over the various guide and stripping elements hereinafter described. The rolls 21 and 22 may feed the tow into a conventional rotary staple cutter 23. The tow enters an axially-extending passage of the rotor 24 and through a radially-extending passageway to be discharged through a port 25 in the periphery of the rotor and thence cut by a knife 26 into fibers which fall into a vessel 27.

The container or trough 17 contains a liquid having a level 30. In the preferred practice of this invention, the liquid is heated by any convenient means, such as the manifolds 31, 32, and 33 which may comprise perforated sections for introducing a heated gas or liquid. The manifolds 31, 32, 33 whether perforated or not, may be connected with a steam supply (not shown). Temperatures of 80° C. to 100° C. may be used. Preferably, the temperature used is as high as can be practically maintained, i. e. around 95° C. Other liquid, which is supplied to container 17 through the inlet 34, may merely be water or it may be a dilute aqueous solution of sulfuric acid, with or without small amounts of the same salts that are carried into the container 17 by the bundle 14. The liquid may be pre-heated before entering container 17 and it is preferably introduced and discharged from the container 17 countercurrent to the direction of movement of the tow 14 through the container. As shown, the liquid inlet 34 is provided at the end of the trough 17 and connected with the lip 37b of the channel 37, through which the tow 14 is discharged. Liquid outlet duct 35 is connected with the lip 37d through which the tow 14 enters the container. The duct 35 is utilized to maintain a predetermined level in the container by extending in an upward direction and terminating at the desired level (see Figs. 2 and 4 for another type of overflow duct). The liquid discharged from duct 35 may be sent to a system for recovering the materials therein, such as sulfuric acid, sodium sulfate, zinc sulfate, or the like.

During operation, the interior of the container is sealed from the outer atmosphere by the lid 19, the lower edge

of which extends entirely around the upper edge of the trough 17 exteriorly thereof and within the peripheral channel, gutter, or moat 37. Liquid is free to pass from within the trough 17 to the peripheral channel 37 through the lips 37b and 37d, but, if desired, additional apertures may be provided in the trough wall to permit liquid flow between the channel 37 and the interior of the trough 17. The four edges of the cover 19 extend, when positioned for operation, into and below the level of the liquid in the channel 37.

A plurality of guides 40 each having an upwardly-facing surface or rounded edge for engaging the tow are supported within the trough 17 at spaced positions from end-to-end of the container. Another series of guides 41, each having a surface or rounded edge which faces downwardly for engagement with the tow, are supported by the cover in spaced relationship with each other. A guide 42 is also supported at each end of the cover 19. The guides 41 and 42 depress the tow into the liquid when the cover has been lowered into position. The guides 40 carry the running tow above the surface of the liquid and the change in direction of the bundle about the first of these guides compacts the bundle and strips off the liquid carried out of the bath by the bundle. A plurality of guides 39, having downwardly-facing tow-engaging surfaces, are supported by the cover and engage the tow along the portions of its path which extend between guides 40 above the liquid. Any suitable means may be employed for supporting the guides 39 and 40 in their positions shown in Figure 1, but preferably adjustable means, as for example as described hereinafter in relation to guides shown in Figures 2 and 3, are utilized. The guides 39 are supported at sufficient height to avoid forcing the tow into the liquid and serve primarily to increase the effectiveness with which liquid is stripped from the tow by the guides 40. As shown, the guides 39 are arranged in alternate positions with respect to the other guides 41 and 42 supported by the cover 19.

The upwardly-facing guides 40 and the downwardly-facing guides 41 and 42 are arranged preferably to produce at least two submerged sections and at least two unsubmerged sections of the tow, the latter being of at least as great a length as the submerged sections.

In connection with the present invention, it has been discovered that filament breakage can be avoided or greatly reduced and that higher strength yarns can be produced from a system involving at least two submerged sections of the filamentary bundle with at least the first submerged section followed by an unsubmerged section in which stripping is effected substantially immediately after the bundle leaves the submerged section. In order to accomplish these benefits and at the same time obtain a high recovery efficiency for the length of the equipment used, the total length of the submerged sections should not exceed the total length of the immediately following unsubmerged sections in which stripping occurs. The ratio between the lengths of the submerged and unsubmerged sections may be between 1 to 1 and 1 to 8 and preferably in the ratio range between 1 to 3 and 1 to 5. In a specific instance, the system may be operated with three submerged sections, each having a length of two feet and followed by an unsubmerged section of nine feet in length, making a total length of thirty-three feet through which the filamentary bundle may pass at such a rate of speed as to give a total time of submergence between one and four seconds. It has been found that by stripping off excess liquid at the beginning of each unsubmerged section, it is not necessary to maintain the filamentary bundle under the liquid for a long period of time or over a great distance in order to obtain high efficiency of recovery at speeds up to 100 meters or more per minute. Because of this discovery, the length of immersion in the heated liquid can be greatly reduced with a consequent reduction in the resistance encountered

in pulling the bundle through the system. It appears that this accounts for the improved strength in the product and its substantial freedom from filament breakage.

Ducts 43 and 44 carried by the cover 19, are provided for conducting the vapors and gases which are discharged from the tow into the enclosed space above the liquid. Ducts 43 and 44 may be subjected to suction by conventional pumps, condensers, or other means (not shown). The vapors removed, such as carbon disulfide and hydrogen sulfide, may be passed through means, such as a condenser, to recover the carbon disulfide and an alkaline medium to remove the hydrogen sulfide.

The tow is led into the trough 17 through the notch or lip 37d in the end wall 38 of the trough 17. This notch extends below the surface of the liquid so that the guide 42 depresses the tow below the level of the liquid as it enters the container. This arrangement for introducing the tow into the container has the further advantages of reducing the length of the trough and the amount of liquid needed for the bath, since the tow gets an initial immersion in the lip 37d as it enters the container. Another guide 42 depresses the tow under the surface of the liquid in the lip 37b as the tow leaves the container 17. A final stripping of the tow is accomplished by the stripping element 37a, supported above the liquid level of the lip 37b.

The liquid of the bath may be directed or circulated in a direction generally counter-current to the movement of the strand 14, to increase the effectiveness of the liquid in washing the strand. For example, baffles 46, 47 and 48, which extend transversely of the interior of the chamber, and from the bottom thereof almost to the level of the bath, may be provided as shown to assure the movement of liquid through the container in a countercurrent direction. These baffles prevent the development of adverse currents, and permit the feeding of the bath liquid to the container at a minimum rate to obtain satisfactorily cleaned tow, with the wash liquid discharged from the container carrying a maximum concentration of suspended and dissolved materials of value.

Fig. 2 illustrates, in section, the details of a modified discharge duct construction which may be adopted at the tow entrance of the container 17, shown in Fig. 1. In the apparatus of Fig. 2, the tow 14 passes through an open-topped duct 50 connected or joined with the end wall of the container 17a. The tow 14 is depressed under the surface 30a of the liquid by guides 41a and 42a. The duct 50 terminates in a rounded edge or lip 51 over which the excess liquid is free to pass into a drain duct 54. The upwardly-facing guides 40a are supported in U-shaped brackets or holders 55 which may be attached to the side wall of the trough 17a by bolts 57 and wing nuts 58. The side portions of the holders 55 are slotted to permit the guides 40a to be individually adjusted to any desired position relative to the surface of the bath. As shown in Fig. 3, holders 60, similar to the holders 55, support the guides 41a in a downwardly-facing position. The holders 60 are adjustably attached to the roof of the cover 19a by the brackets 62 and 63. As shown in Fig. 3, the cover 19a is supported on a hinge which pivots at 64 with respect to a stationary mounting 65 to aid in raising and lowering the cover. The cover may be counterbalanced in conventional manner by a counterweight acting on a cable 67 attached to the cover 19a by a bracket 68. The cover 19a is provided with one or more short exhaust ducts 43a which move with the cover 19a when opened, and are connected, as by flexible duct 43b, with suction generating apparatus (not shown).

The guide holders 55 and 60 of the apparatus shown in Figs. 2, 3 and 4 are adapted (as shown in cross section by Fig. 2) to receive guides of non-abrasive and corrosion-resistant material, such as the guide 70 shown in Fig. 5. This guide is provided with side projections 71 which prevent the tow from escaping laterally from the guide sur-

face 72. Satisfactory materials for forming guides 70 are cemented and fused aluminum oxide, glass, glazed ceramic materials, and synthetic sapphire. The guides 70 are merely pushed into retaining flanges of the holders 55 and 60 and are readily replaceable.

Fig. 6 shows a modified system for supporting the cover 19c of such an enclosed system. As shown, the cover is suspended from a stationary overhead support 75 by a plurality of cables 73 (two being shown) which pass over pulleys 76 and are counterweighed by weights 77.

The apparatus illustrated in Figs. 2 and 3 is especially adapted for the rapid lacing of the tow between the upwardly-facing guides supported in the container 17a and the downwardly-facing guides supported by the cover 19a. The oppositely-facing guides are separated when the cover is lifted and once the tow extended over the upwardly-facing guides, the cover is lowered into position, lacing the apparatus for use. However, under some operating conditions, an arrangement may be preferred whereby the cover may be raised or lowered without disturbing the path of the tow during its movement through the apparatus, that is, the movement of the cover should not affect the position of the downwardly-facing guides, such as guides 39, 41 and 42 of Fig. 1, of which the guides 41 and 42 force the tow below the level of the bath. This arrangement would permit the passage of the tow through the container along its normal operating path during operation for the bath without substantially interfering with the treatment of the tow, even though the cover is raised.

In Figs. 7 and 8, a modified apparatus is illustrated in which all guides for the filamentary tows 80 and 81 are attached to a liquid container 82 independently of a cover 83. A pair of downwardly-facing guides 85 and 86, positioned transversely of the container 82 to separately engage tows 80 and 81, are mounted in a single holder 87, adjustably secured to a post 88 by a stud 89 passing through a vertical slot 90 in the post 88. The holder 87 is provided with a saddle portion 91 engaging the peripheral surface of the post to maintain the holder in a fixed horizontal alignment. A wing nut 93 is threaded onto the stud 89 and turned tightly against a saddle washer 92, securing the holder 87 in fixed position on the post 88.

The holder 97, for supporting the upwardly-facing guides 95 and 96, may be similar to that just described with regard to the guides 85 and 86, except that its position is inverted with respect to that of the holder 87. The holder 97 is supported by a slotted post 98, similar to the post 88 and spaced lengthwise therefrom. Gaseous material separated from the tow may be withdrawn from the region over the bath enclosed by the cover 83 through a plurality of conduits, such as conduit 99, which extends upwardly through the bottom of the container 82 with its open end disposed above the bath. The various ducts 99 are connected with a manifold 100 which conducts such gaseous materials away from the apparatus.

Thus, the present invention provides a simple and practical apparatus for washing and separating impurities from a freshly-spun multi-filament strand, involving passing the strand over a path which leads into and out of a countercurrent stream of liquid according to an arrangement not heretofore known and appreciated. The invention is especially adapted for cleaning bulky strands, such as those known as tows, which comprise many thousands of regenerated cellulose filaments, and to collect the materials washed therefrom in sufficient concentration to render the recovery thereof practical. Moreover, the processing system provided is completely closed, a feature which reduces materially the exposure of personnel to obnoxious and toxic gases and liquids which accompany the preparation of such strands or tows of regenerated cellulose or staple fiber manufactured therefrom, for the trade. A primary advantage of the present invention is, of course, the economical use of factory space and labor.

While preferred embodiments of the invention have

been shown and described, it is to be understood that changes and variations may be made without departing from the spirit and scope of the invention as defined in the appended claims.

5 We claim:

1. An apparatus for treating a continuous running filamentary bundle including a container having a bottom wall and a pair of longitudinal side walls between which said filamentary bundle is adapted to travel, a plurality 10 of longitudinally spaced baffles extending between said side walls and dividing said container into a number of individual compartments, means at one end of said container for feeding liquid into said container to a level extending above the top portions of said baffles, means at 15 the end of said container opposite said liquid feed means for discharging liquid from said container, said liquid feed and discharge means cooperating to maintain the liquid level in said container at an approximately constant plane and providing a liquid flow in a countercurrent direction 20 to the travel of said filamentary bundle, a first and a second series of stationary guide elements extending transversely of said container, said guide elements each having a surface adapted to engage with the filamentary bundle during its travel through said container, means 25 for supporting the guide elements of said first series with their bundle engaging surfaces extending downwardly toward the container bottom wall and below the liquid level plane, said guide elements of said first series being spaced apart longitudinally of said container with at least one 30 guide element extending into each of said compartments, said second series of guide elements being supported by said container with their bundle engaging surfaces extending in an upward direction away from the container bottom wall and above the liquid level plane, said guide 35 elements of said second series being spaced apart longitudinally of said container with at least one guide element extending above each compartment intermediate the guide elements of said first series and adjacent the baffle located therebetween, and means for tensioning the filamentary bundle whereby said first and second series of guide elements are adapted to cause the filamentary bundle to travel a sinuous path through said container with the guide elements of said first series sequentially depressing the bundle within each of said compartments while the guide elements of said second series elevate the bundle above the liquid level plane and strip the excess liquid therefrom after each such bundle depression.

2. An apparatus as set forth in claim 1 wherein at least one pair of guide elements of said second series extend above each compartment intermediate the guide elements of said first series and adjacent the baffle located therebetween, and further including a third series of stationary guide elements each having a bundle engaging surface, means for supporting the guide elements of said 50 third series with their bundle engaging surfaces extending downwardly toward said bottom wall to a position intermediate the liquid level plane and a plane passing through bundle engaging surfaces of the guide elements of said second series, said guide elements of said third series being spaced apart longitudinally of said container with at least one of said guide elements of said third series being disposed between each pair of guide elements of said second series.

3. An apparatus for treating a continuous running filamentary bundle including a container having a bottom wall and a pair of longitudinal side walls between which said filamentary bundle is adapted to travel, means at one end of said container for feeding liquid into said container, means at the end of said container opposite from said liquid feed means for discharging liquid from said container, said liquid feed and discharge means cooperating to maintain the liquid level in said container at an approximately constant plane and providing a liquid flow in a countercurrent direction to the travel of said filamentary bundle, a first and a second series of stationary

guide elements extending transversely of said container, said guide elements each having a surface adapted to engage with the filamentary bundle during its travel through said container, support means carrying the guide elements of said first series in spaced apart relationship longitudinally of said container with their bundle engaging surfaces extending downwardly toward the container bottom wall and below the liquid level plane, said second series of guide elements being supported by said container with their bundle engaging surfaces extending in an upward direction away from the container bottom wall and above the liquid level plane, said guide elements of said second series being spaced apart longitudinally of said container with at least one guide element being disposed intermediate adjacent guide elements of said first series, means for tensioning the filamentary bundle during its travel through said container whereby the filamentary bundle is caused to travel a sinuous path through said container with the guide elements of said first series sequentially depressing the bundle below the liquid level plane while guide elements of said second series elevate the bundle above the liquid level plane and strip the excess liquid therefrom after each such bundle depression.

4. An apparatus as defined in claim 3 wherein at least one pair of guide elements of said second series is disposed between adjacent guide elements of said first series, and further including a third series of guide elements, each having a bundle engaging surface, said guide elements of said third series being carried by said support means with their bundle engaging surfaces extending downwardly toward said bottom wall to a position intermediate the liquid level plane and a plane passing through the bundle engaging surfaces of the guide elements of said second series, said guide elements of said third series being spaced apart longitudinally of said container with at least one of said guide elements of said third series being disposed between each pair of guide elements of said second series.

5. An apparatus for treating a continuous running filamentary bundle, a container having a bottom wall and a pair of longitudinal side walls between which said filamentary bundle is adapted to travel, means at one end of said container for feeding liquid into said container, means at the end of said container opposite from said liquid feed means for discharging liquid from said container, said liquid feed and discharge means cooperating to maintain the liquid level in said container at an approximately constant plane and providing a liquid flow in a countercurrent direction to the travel of said filamentary bundle, peripheral channel means carried by the side walls of said container and communicating with the interior of said container at a level below said liquid level plane, a cover adapted to be disposed over said container with portions thereof received within said peripheral means, said cover cooperating with said peripheral means to enclose the portion of said container above the liquid level from the atmosphere, a first and a second series of stationary guide elements extending transversely of said container, said guide elements each having a surface adapted to engage with the filamentary bundle during its travel through said container, support means carrying the guide elements of said first series in spaced apart relationship longitudinally of said container with their bundle engaging surfaces extending downwardly toward the container bottom wall and below the liquid level plane, said second series of guide elements being supported

by said container with their bundle engaging surfaces extending in an upward direction away from the container bottom wall and above the liquid level plane, said guide elements of said second series being spaced apart longitudinally of said container with at least one guide element being disposed intermediate adjacent guide elements of said first series, means for tensioning the filamentary bundle during its travel through said container whereby the filamentary bundle is caused to travel a sinuous path through said container with the guide elements of said first series sequentially depressing the bundle below the liquid level plane while guide elements of said second series elevate the bundle above the liquid level plane and strip the excess liquid therefrom after each such bundle depression.

6. An apparatus as described in claim 5, further including exhaust means for expelling gas and liquid vapors from the enclosed portion of said container above the liquid level plane.

7. An apparatus for treating a continuous running filamentary bundle including a container having a bottom wall and a pair of longitudinal side walls between which said filamentary bundle is adapted to travel, means at one end of said container for feeding liquid into said container, means at the end of said container opposite said liquid feed means for discharging liquid from said container, said liquid feed and discharge means cooperating to maintain the liquid level in said container at an approximately constant plane and providing a liquid flow in a countercurrent direction to the travel of said filamentary bundle, a first and a second series of stationary guide elements extending transversely of said container, said guide elements each having a surface adapted to engage with the filamentary bundle during its travel through said container, support means carrying the guide elements of said first series in spaced apart relationship longitudinally of said container with their bundle engaging surfaces extending downwardly toward the container bottom wall and below the liquid level plane, said second series of guide elements being spaced apart longitudinally of said container with at least one guide element being disposed intermediate adjacent guide elements of said first series, means for tensioning the filamentary bundle during its travel through said container whereby the filamentary bundle is caused to travel a sinuous path through said container with the guide elements of said first series sequentially depressing the bundle below the liquid level plane while guide elements of said second series elevate the bundle above the liquid level plane and strip the excess liquid therefrom after each such bundle depression.
